UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

THERMOSTAT.

1,190,061.

Specification of Letters Patent.

Patented July 4, 1916.

Application filed June 25, 1914. Serial No. 847,340.

To all whom it may concern:

Be it known that I, JAMES J. Wood, a citizen of the United States, residing at Fort Wayne, county of Allen, State of Indiana, have invented certain new and useful Improvements in Thermostats, of which the following is a specification.

My invention relates to thermostats, and particularly to the improved construction and arrangement of the parts constituting such an instrument.

In instruments of this character, especially where they are designed to operate on circuits of a considerable voltage, it is desirable that the opening and closing of the circuit should be positive and quick in order to prevent arcing at the contacts, and that the instrument should be sensitive and readily adjustable.

My object has been, therefore, to produce an instrument which will operate in the manner outlined above, and at the same time will be compact, strong, accessible, and in general an efficient instrument.

Another object of my invention is to provide a thermostat having a movable contact member distinct from but connected with the thermostatic element and to provide a novel suspension for this member.

Still another object is to provide anti-friction bearings for the movable contact member mentioned above.

Further objects of my invention will appear from the detailed description and the claims appended thereto.

Briefly, my thermostat comprises a supporting plate carrying a centrally arranged stud to which one end of a spirally coiled spring which constitutes a thermostatic element is connected. Overlying this spring and oscillating across a vertical axis is a contact arm or bar pivoted at its lower end on a stationary bearing. The free end of the spring is pivotally connected to this bar just above the stationary bearing and when it contracts or expands, due to changes in temperature, moves the bar to one side or the other of the vertical. The spring and stationary bearing constitute a suspension for the contact bar. Preferably, the contact bar is engaged by one of these bearings at two separated points and by the other at an intermediate point, thus forming a three point suspension. Both of the elements of

the suspension are provided with anti-friction bearings where they engage the contact bar; in this case with knife edges engaging V-shaped grooves. Two spring contacts, insulated from the supporting plate, are arranged at either side of the upper end of the contact arm and frictionally engage the same, while supported on the same posts with the contact springs are stops limiting the movement of the contact arm. At the rear end of the stud which supports the thermostatic element, a worm and gear adjusting means is provided for adjusting the instrument so that it will operate at the desired temperature.

One of the many applications of my device is to refrigerating machines. In such an arrangement the contacts will be arranged to close a circuit to energize the coil of an electromagnetically operated switch when the contact arm moves to the left, for instance, and when it moves to the right will form a short circuit around this same coil, thereby taking care of the inductive kick.

I have more fully described my invention in the following specification, referring to accompanying drawing, in which:

Figure 1 is a front elevation with the cover removed; Fig. 2 is a side elevation, looking at the left of Fig. 1, showing the cover in section; Fig. 3 is a top view with the cover in section; Fig. 4 is a detail showing the worm and gear adjusting means; and Fig. 5 is a diagrammatic view showing the circuits when the thermostat is connected in the manner suggested above.

A supporting plate 10, preferably circular, is supplied with legs 11 by which it is intended that it shall be attached to a vertical surface. These legs are offset in such a way that the supporting plate is held out from the surface to which the instrument is applied, in order to accommodate certain parts projecting from the back of the plate. It will be noted also that the supporting legs project beyond the outer circumference of the plate, so that the instrument may be readily secured from the front. A stud 12 is rotatably attached at the center of the plate and is provided with a flange 13 abutting against the front thereof. At the back of the plate a worm gear 14 is applied to this stud and secured by means of a nut 15. For the purpose of adjusting this stud to any

desired position, a worm 17 is supported by a stud 16 in operative relation with the gear 14. This worm is provided with a slotted head 18 projecting beyond the outer circumference of the supporting plate, whereby it may be easily turned.

The forward end of the stud 12 is slotted to admit one end of a thermostatic element formed as a spiral spring 20. This spring 10 will respond to changes in temperature by expanding or contracting, and is preferably constructed in the usual manner out of two elements having different coefficients of expansion. As will be seen in Fig. 2, the 15 outer end of the spring is reduced in width at 21 and provided with a slot 22 for a purpose to be later explained. This reduced end is turned at practically right angles with the main portion of the spring and is 20 sharpened to provide a knife edge for engagement with a pivoted contact arm, as shown in dotted lines in Fig. 1. This contact blade or bar 30 is a U-shaped member whose central portion overlies the spring 25 20 and whose legs 37 and 33 project inwardly above and below this spring. The lower leg 33 is provided with a V-shaped groove on its upper edge in which the sharpened edge of the spring 20 engages (see Fig. 1). 30 Adjacent the ends of this leg are depending feet 34 provided with an upwardly extending V-shaped groove. These grooved feet rest upon a stationary bearing in the form of a knife edge 32 held in a stud 31 attached 35 to the supporting plate. At approximately the center of the lower leg 33 a pin 35 is provided, which projects into the slot 22 and prevents displacement of the end of the spring in the groove. The upper leg 37 is 40 provided on its upper side, adjacent the end, with a contact piece 38 which may be constructed of silver or any other non-corrosive conductor.

The pivoted contact arm 30 co-operates at 45 its upper end with fixed contacts held in binding posts 40 and 40'. The binding posts pass through apertures in the supporting plates 10 larger than the posts and are fixed in metal plates 41 suitably insulated from the plate 10 by means of pieces of insulation 42, the whole being held in position by means of insulated screws. Adjacent their outer ends, the binding posts 40 and 40' are slotted to receive spring contact members 43, which are slotted, as will be seen from Figs. 2 and 3, and are provided at the lower side of their free ends with contacts 44 which may be constructed of silver or a similar metal. Supported 50 upon the posts 40 and 40', at a point inside the spring contacts, are fixed stops 45 which limit the motion of the upper leg 37 of the pivoted contact arm. By this arrangement, it is unnecessary to separately insulate the 55 stops 45 from the plate 10. At some con-

venient point a third binding post 46 is electrically connected with the plate 10 and thereby, through the members 31 and 32, with the contact arm 30.

The instrument is preferably provided 70 with a cover 50 fitting in a groove 54 in the plate 10 and held in place by screws 51. This cover is provided with a transparent closure 52.

The instrument may be applied to any device 75 in which it is desired to open and close a circuit in response to changes in temperature. One manner of application is illustrated in Fig. 5. Here the mains 60 supply energy from a source of power (not shown). 80 If the contact arm 30, electrically connected through the supporting plate with the binding post 46, is moved to the left until it touches the spring attached to binding post 40, then the operating coil 61 of an electromagnetically operated switch will be energized from the mains 60 and the contacts 62, forming the terminals of any desired circuit, will be closed. In the preferred arrangement of my invention, the 85 binding post 40' is connected to one terminal of the circuit which was closed, here one terminal of the coil 61, in such a manner that when the contact arm 30 touches the spring attached to the binding post 40', the inductive portion of the circuit, here the coil 61, is short-circuited. Because of the 90 particular arrangement of the parts, as later explained, the time interval between the opening of the circuit and the closing 95 of the short circuit is very small, and any arc which may be formed by the opening of the inductive circuit will be quickly extinguished. 100

It will be seen from an inspection of Fig. 1, that the contact arm frictionally engages the spring contacts 43 in such a way that some little pull is required to disengage the same. This will insure a positive and quick opening of the circuit, similar to that found in the well known snap switch, and prevent chattering and arcing at the contacts. Because of the frictional engagement of the contact spring and the contact arm, the temperature must vary to a considerable extent, say, for instance, 10° above or below the desired mean, before the arm 30 will be pulled over by the spring 20 from one spring contact 43 to the other, and that a considerable torque will have been thereby 110 developed which will insure positive and quick action both in opening the short circuit and in energizing the other circuit. By means of the particular relations of the various elements, it will be seen that I am 115 enabled to make my temperature responsive spring 20 of considerable width, and that as a result the torque developed thereby will be comparatively large. It should be further noted that the contact arm oscillates 120 125 130

about a vertical plane through the knife edge 32, and that, therefore, it cannot readily find a position of stable equilibrium between the two spring contacts. Further, the particular relation of the feet 34 and the reduced end 21 of the spring constitutes a three-point suspension for the contact arm, the points of engagement being provided with anti-friction bearings. By means of the head 18 and the coöperating worm and gear, the stud 12 may be readily adjusted to any desired position, thereby adjusting the tension of the spring so that it will respond to any desired temperature.

I conceive that various modifications of the details of the particular arrangement which I have shown may be made, and I, accordingly, do not desire to be limited to the exact construction shown other than as I am limited by the terms of the appended claims, but I wish it understood that my invention extends not only to the broad general arrangement of the parts, but, as well, to the specific details of my device as shown.

What I claim as new and desire to secure by Letters Patent of the United States, is,—

1. A thermostatic switch comprising a movable contact bar having a leg extending at right angles thereto, a stationary support pivotally engaging with one side of said leg, a coiled thermostatic element pivotally engaging with the opposed side of said leg, one of said coacting bearings engaging with said leg at two points and the other engaging at an intermediate point, and a frictional contact on each side of said contact bar to engage with and temporarily hold said contact bar.

2. A thermostat comprising a horizontal knife-edge support, a movable contact arm provided with a V-shaped groove resting upon said support and extending upwardly therefrom, said arm being provided with another V-shaped groove above the first-named groove, means responsive to changes in temperature having a moving part resting in said upper groove, and a fixed contact coöperating with the upper end of said arm.

3. A thermostat comprising a flat supporting plate adapted to be arranged in a vertical plane, a knife-edge support perpendicularly attached to said plate, the knife-edge pointing upwardly, a stud attached to said plate above said support, a spirally coiled thermostatic element attached to said stud and having its free end normally adjacent to and above said support, a fixed contact, a movable contact arm coöperating therewith, said arm having an offset leg at its lower end, said leg having a V-shaped groove in its upper side receiving the free end of said thermostatic element intermediate the ends of the leg, feet adjacent the ends of said leg having a V-shaped groove

on their lower edges and bearing on said knife-edge support.

4. A thermostat comprising a flat supporting plate adapted to be arranged in a vertical plane, a contact arm pivoted to said plate at its lower end and arranged so that its upper end oscillates across a perpendicular axis through the pivot point, thermostatic means connected to said arm for moving the same, binding posts insulated from each other and said arm attached to said plate on opposite sides of said axis adjacent the upper end of said arm, and contact springs carried by said posts curved to frictionally engage and temporarily retain said arm in contact therewith.

5. A thermostat comprising a flat supporting plate adapted to be arranged in a vertical plane, a contact arm pivoted to said plate at its lower end and arranged so that its upper end oscillates across a perpendicular axis through the pivot point, thermostatic means connected to said arm for moving the same, binding posts insulated from each other and said arm attached to said plate on opposite sides of said axis adjacent the upper end of said arm, contact springs carried by said posts curved to frictionally engage and temporarily retain said arm in contact therewith, and stop members for said arm also carried by said binding posts.

6. A thermostat comprising a supporting plate, offset legs for attaching said plate to a vertical support, a substantially centrally arranged rotatable stud carried by said plate, a worm gear on said stud behind said plate, a worm for rotating said gear, a spirally coiled spring in front of said plate having its inner end attached to said stud, a U-shaped contact arm having its central portion overlying said spring in an approximately vertical position, means for pivotally supporting the lower leg of said contact arm at points adjacent its ends, said leg being provided with a V-shaped groove in its upper side, the outer end of said spring being reduced in width and sharpened to engage said groove intermediate the ends of said leg, flexible contacts supported by but insulated from said plate at each side of and above said spring and coöperating with the upper leg of said arm to frictionally engage the same, and stops adjacent said contacts.

7. A thermostatic switch comprising a movable contact bar having a leg extending at right angles thereto, a thermostatic element having a knife edge bearing upon the leg to move the contact bar, and a similar stationary bearing for the contact bar coöperating with the bearing of the thermostatic element to constitute a suspension for said bar.

8. A thermostatic switch comprising a movable contact bar having an offset leg at each end, a thermostatic element having an

anti-friction bearing upon one offset leg to operate the same, a similar stationary bearing for the movable bar, one of said bearings having two points of engagement, and 5 the other a single point between the two points, thereby forming a three-point suspension for the bar, and one or more fixed contacts frictionally engaging with the off-

set leg of the contact bar opposite said bearings.

10

In witness whereof, I have hereunto set my hand this 22nd day of June, 1914.

JAMES J. WOOD.
